Letters Patent No. 2382, Dated Aug. 14. 1866.

Design for Coffin Trimmings.

The schedule referred to in this Letter Patent and making part of the same,

To all whom it may concern:

Be it known that S. D. Arnold of New
Britain Hartford County and State of Connecticut have
invented a new Design for Trimmings for Coffins and other
Burial Cases, and I do hereby declare that the following is a full clear
and exact description thereof, which will enable others skilled in
the art to make and use the same, reference being had to the accom-
panying drawing forming part of this Specification.

The present invention consists of an ornamental
plate to be used upon the sides or top, or other desired portions
of coffins and other burial cases which Design is illustrated
in the accompanying plate, the

Figure being a photographic view of the same.

A, in the plate represents the plate, which in outline is of
the general form of a cone, having in its center, or the center, a
rose B, surrounded upon both of its sides and above it, by
a series of rose leaves C, rose bush D, and stems E, with the lower
end of the plate terminating with a rose bush branch F, from which
extind leaves G.

I claim as new and desire to secure by Letters Patent,
The Design herein described, and shown in the accompanying plate.
